(57) **CLAIM**

The ornamental design for a beer bottle opener, as shown and described.

DESCRIPTION

FIG. 1 is a perspective view of a beer bottle opener;
FIG. 2 is a front elevation view thereof;
FIG. 3 is a rear elevation view thereof;
FIG. 4 is a side elevation view thereof, the opposite side elevation view being a mirror image thereof; and,
FIG. 5 is a top plan view thereof.
The bottom surface of the beer bottle opener is flat and devoid of surface ornamentation.
